(57) **CLAIM**

The ornamental design for a coldness/heat preserving container, as shown and described.

DESCRIPTION

FIG. 1 is a perspective view of the coldness/heat preserving container showing my design;

FIG. 2 is a front elevational view thereof, the rear view being identical thereto;

FIG. 3 is a top plan view thereof, the bottom view being identical thereto;

FIG. 4 is a right side view thereof;

FIG. 5 is a left side view thereof; and,

FIG. 6 is another perspective view, showing several individual units of the coldness/heat preserving container stacked on one another.

The broken line showing of ice packs is included for the purpose of illustrating and forms no part of the claimed design.
